UNITED STATES PATENT OFFICE.

DON EDWARD McDONALD, OF BATAVIA, NEW YORK, ASSIGNOR TO RALPH E. CHAPIN, OF SAME PLACE.

OIL-CAN.

SPECIFICATION forming part of Letters Patent No. 664,093, dated December 18, 1900.

Application filed July 25, 1900. Serial No. 24,785. (No model.)

To all whom it may concern:

Be it known that I, DON EDWARD McDONALD, a citizen of the United States, residing at Batavia, in the county of Genesee and State 5 of New York, have invented new and useful Improvements in Oil-Cans, of which the following is a specification.

This invention relates to oil and gasolene cans which are designed more especially for 10 domestic or family use and which are provided with a hand-pump and telescopic discharge-pipe the upper section of which can be lowered when not in use or raised to permit a lamp-bowl or other vessel to be placed 15 under its spout.

The principal object of my invention is to provide the can with a simple pump of comparatively large capacity which permits the instant stoppage of the flow of oil from the 20 pump when the lamp-bowl or other receptacle is filled, so as to prevent overflowing of the vessel, and which allows the pump-plunger and the upper movable section of the telescopic discharge-pipe to be pushed down into 25 the can immediately after filling the vessel without discharging or spattering the oil over the top of the can, thus enabling the cover to be closed at once after filling a vessel.

My invention has the further object to im- 30 prove the construction of the can in other respects with a view of rendering the same more convenient in use.

In the accompanying drawings, Figure 1 is a vertical section of an oil-can provided with 35 my improvements. Fig. 2 is a top plan view thereof, on a reduced scale, with the cover omitted. Fig. 3 is an enlarged sectional elevation of the upper portion of the hollow plunger-rod and the cover of the pump-barrel 40 at right angles to Fig. 1, showing the means for interlocking said cover with said rod. Fig. 4 is a top plan view of said cover. Figs. 5 and 6 are horizontal sections in lines 5 and 6, Fig. 1.

Like letters of reference refer to like parts in the several figures.

A is the body of the can, and A' its head or top plate, having the usual depressed central portion or pan A², provided with the drain 50 opening or nipple a.

B is the circular lid or cover applied to the

depressed portion A² of the head and preferably hinged thereto in a well-known manner.

C is the upright pump-barrel arranged in the can and having its open upper end secured in an opening formed in the head A'. The pump-barrel extends to the bottom of the can and is provided at its lower end with lateral inlet-openings c and immediately above said openings with a diaphragm D, having a passage d, which is controlled by an upwardly-opening valve d'. This valve preferably consists of a flat disk resting loosely upon the diaphragm D and held against displacement by a suitable cage d², secured 65 to the diaphragm. The valve d while permitting the oil to rise through the passage of the diaphragm checks its return through the same.

E is the lower stationary section of the telescopic discharge-pipe of the pump, which is connected with the pump-barrel above the diaphragm D and which extends upwardly through the head A' of the can.

E' is the upper movable section of the telescopic discharge-pipe, which slides in the lower section and is provided at its open lower end with a plunger or packing e for forming a tight joint.

e² is the usual spout of the movable pipe-section which enters the drain-nipple a when in its depressed position.

The discharge-pipe E E' contains no check-valve or other obstruction, so that the oil in said pipe is free to return into the pump-barrel.

F is the plunger of the pump, which is suitably packed to form an air-tight joint around its periphery and which is provided with a port or passage f, through which the oil is allowed to pass upwardly into the portion of the pump-barrel above the plunger when said passage is unobstructed.

f' is an upwardly-opening relief-valve applied to the plunger-passage f and consisting, 95 preferably, of a flat disk adapted to rest upon the upper side of the plunger and confined against displacement by a raised yoke or cage g.

h is the plunger-rod, which is preferably 100 hollow and connected with the plunger by the yoke g. This rod extends upwardly through

the open upper end of the pump-barrel and is provided at its upper end with a cross-bar h' , forming a handle for operating the plunger.

5 i is an operating-rod connected with the relief-valve f' and extending upwardly through the hollow plunger-rod h and terminating in an eye or knob i' , whereby said valve may be held down on its seat by the same hand with which the operator grasps the handle of the 10 plunger-rod.

j is a removable head or cover which closes the upper end of the pump-barrel. The upper end of the latter is flared or funnel-shaped, as shown at k , to facilitate the pouring of the 15 oil into the pump-barrel in filling the can, and the barrel is provided immediately below its flared portion with openings l , through which the oil poured into the barrel flows into the body of the can. The cover j of the pump-barrel is seated on a shoulder m , formed at the upper end of the pump-barrel, and is provided in its edge with a radial notch m' , which receives the adjacent portion of the stationary discharge-pipe E . The latter is provided 20 at its upper end with an outwardly-projecting annular flange or bead m^2 , which overlaps the edge of said notch and prevents upward displacement of the cover. The cover may be further held down in place by a turn-button n , pivoted to the head of the can. The cover is preferably raised and removed by means of the plunger-rod h , which passes through a central opening of the cover. For this purpose the cover j is provided on its upper side concentrically with the plunger-rod with a collar o , having L-shaped slots o' in diametrically opposite sides thereof. These 30 slots are adapted to receive the end portions of the cross-bar h' of the plunger-rod, which bar after being passed downwardly to the lower ends of the vertical branches of said slots is caused to enter their horizontal branches by giving the plunger-rod a partial forward turn. When the cover is thus interlocked with the plunger-rod and released from the turn-button n , the same can be raised by means of the valve-rod i and withdrawn laterally from under the flange m^2 at the upper 40 end of the stationary discharge-pipe E . In removing the barrel-cover the plunger-rod is raised through the medium of the relief-valve f' , which comes in contact with the under side of the yoke g and acts as a stop which limits the upward movement of the valve-rod i in 45 the plunger-rod. The plunger-rod is readily detached from the cover by turning the same backward sufficiently to release its cross-bar from the slots o' in the collar o of the cover.

In filling a lamp-fount or other vessel the 50 movable section E' of the telescopic discharge-pipe is raised and the fount placed under its spout in the usual manner. The operator then grasps the plunger-rod h by placing the fingers under its cross-bar h' and the thumb 55 of the same hand upon the eye i' of the valve-rod i , so as to hold the relief-valve in its closed position, as shown in the drawings.

The plunger now acts like the solid plunger of an ordinary single-acting pump, and upon raising the same the oil is drawn through the 70 inlet-openings c of the barrel and the suction-passage d into the barrel. Upon depressing the plunger the suction-valve d' is closed and the oil below the plunger is forced through the discharge-pipe $E E'$ into the vessel to be 75 filled. The pump-barrel preferably has a comparatively large capacity—say about a quart—so that a fount of ordinary size can be filled with a single stroke of the plunger. The delivery of the oil may be instantly 80 stopped by simply releasing the rod i of the relief-valve f' , when the oil in the pump-barrel below the plunger will open said valve and rise through the passage f of the plunger, and the oil in the discharge-pipe $E E'$ 85 will descend and a portion thereof return into the lower portion of the pump-barrel and ascend through the plunger-passage, the oil ascending through the plunger until it reaches the same level as the oil in the body of the 90 can. After filling the vessel the plunger and the vertically-movable section E' of the discharge-pipe can be immediately pushed down to their lowermost position, in which position they permit the cover of the can to be closed, 95 and this is accomplished without discharging or spattering the oil, which ordinarily remains in said pipe, over the top of the can. This objection is overcome by the use of my improved pump, because the oil in the 100 discharge-pipe is free to immediately settle therein and rise through the plunger-passage f past the relief-valve f' , which latter opens automatically under the upward pressure of the oil. In oil-cans of this class as hitherto 105 constructed the plunger and the discharge-pipe could not be pushed down into the can immediately after filling a vessel without discharging the oil which remains in the delivery-pipe, because the check-valve in said 110 pipe prevented the return of the oil into the pump-barrel and the oil was therefore expelled from the pipe upon telescoping the same. To avoid this objection in such cans, the oil remaining in the discharge-pipe must 115 be allowed to settle and leak past the valve in said pipe; but servants frequently do not wait until this occurs, and as a consequence forget or neglect to close the cover of the can, allowing the odor or vapor of the oil to escape 120 into the room and rendering the can unsafe. By constructing the pump so that the plunger and the discharge-pipe can at once be lowered after filling a vessel the cover 125 can be closed immediately and the duty of closing the same is therefore not likely to be forgotten or neglected.

When it is desired to fill the can, the plunger-rod h is interlocked with the cover j of the pump-barrel, as hereinbefore described, 130 and said cover is then removed. Oil is then poured into the flared upper end of the barrel, from which latter it flows through the upper openings l of the barrel into the can-body.

By thus utilizing the barrel itself as a filler the use of a separate funnel is dispensed with and the oil-can can be filled in less time than by the use of a funnel placed in an opening or nipple in the head of the can.

The cover *j* of the pump-barrel is confined upon the plunger-rod by the cross-bar *h'*, and the cover cannot therefore become lost or mislaid.

10 I claim as my invention—

1. In an oil-can, the combination with the body of the can, of a force-pump arranged therein and having its barrel provided in its lower portion with an inlet which communicates with the liquid-space of the can, a check-valve applied to said inlet for preventing the return of the oil from the barrel into the can, a valveless discharge-pipe which is connected with the pump-barrel above said check-valve and which permits any oil in said pipe to return into the pump-barrel, a plunger arranged in the pump-barrel and provided with a relief-passage through which the oil may ascend above the plunger, and a relief-valve applied 25 to said plunger-passage and provided with a closing-handle which extends to the upper end of the pump-barrel, substantially as set forth.

2. In an oil-can, the combination with the body of the can, of a force-pump arranged therein and having its barrel provided in its lower portion with an inlet which communicates with the liquid-space of the can, a check-valve applied to said inlet for preventing the return of the oil from the barrel into the can, a telescopic discharge-pipe which is connected with the pump-barrel above said check-valve and which is unobstructed throughout its length, a plunger arranged in the pump-barrel and provided with a relief-passage and a hollow operating-rod extending above the barrel and terminating in a handle, and an up-

wardly-opening relief-valve applied to said plunger-passage and provided with an operating-rod which extends upwardly through 45 said plunger-rod and which terminates in a handle arranged adjacent to the handle of the plunger-rod, substantially as set forth.

3. In an oil-can, the combination with the can-body and its head having an opening, of 50 a pump-barrel having its open upper end secured in said opening, a delivery-pipe connected with the pump-barrel and extending upwardly through the head of the can and provided at its upper end with a projecting 55 flange, and a removable cover seated in the upper end of the pump-barrel and provided in its edge with a notch which receives the flanged upper end of said delivery-pipe, substantially as set forth. 60

4. In an oil-can, the combination with the body of the can, of a pump-barrel arranged in the can and having an open upper end, the plunger arranged in the barrel, a removable cover applied to the upper end of the pump-barrel and coöoperating locking devices arranged on said cover and the plunger, substantially as set forth. 65

5. In an oil-can, the combination with the body of the can, of a pump-barrel arranged 70 in the can and having an open upper end, a removable cover applied to the upper end of the pump-barrel and having a collar provided in opposite sides with L-shaped slots, and a plunger arranged in said barrel and provided 75 with a cross-bar adapted to engage in said slots, substantially as set forth.

Witness my hand this 21st day of July, 1900.

DON EDWARD McDONALD.
